CYCLE SADDLE

Arthur David Hayes and Andrew J. Linder,
Elyria, Ohio, assignors to The Troxel Manufacturing Company, Elyria, Ohio, a corporation of Ohio

Application August 24, 1936, Serial No. 97,588

5 Claims. (Cl. 208—15)

This invention relates to cycle saddles, and more particularly to a cycle saddle having a receptacle integrally formed therein.

We are familiar with prior cycle saddles where-
5 in a separate tool or the like receptacle is sup-
ported by the saddle, usually by being suspended
from the saddle rear wall.

We are also familiar with a co-pending applica-
tion of Roland W. Faulhaber, filed June 19, 1935,
10 Serial No. 27,312 which issued into Patent No. 2,057,374 under date of October 13, 1936 wherein
a receptacle is integrally formed with the saddle
and a portion of the rear wall of the saddle is
movable to provide access to the receptacle, the
15 receptacle wall being formed of flexible material
such as leather.

The present invention is somewhat similar to
the saddle described in the said Faulhaber patent
but in our invention the receptacle walls are
20 formed of relatively rigid material such as metal,
thereby re-enforcing the saddle in this zone and
providing a more rugged construction.

The present construction is relatively economical
25 of manufacture and assembly, and due to the
rigid construction, the closure element for the
receptacle may comprise either a hinge construc-
tion or a drawer movable outwardly from the
receptacle and in either instance forming a por-
30 tion of the saddle rear wall when in closed posi-
tion.

It is an object of our invention, therefore, to
provide a cycle saddle having a rigid built-in re-
ceptacle which forms a re-enforcement for the
saddle.

35 Another object of our invention is to provide a
cycle or the like saddle having a metal receptacle
formed in the rear portion thereof having a rigid
closure member comprising a portion of the saddle
rear wall in closed position.

40 Another object of our invention is to provide a
cycle or the like saddle having a built-in receptacle
and which receptacle is relatively economical
of manufacture and assembly.

45 Another object of our invention is to provide a
cycle or the like saddle having a built-in receptacle
comprising a drawer removably disposed
therein.

50 Other objects of our invention and the inven-
tion itself will become increasingly apparent from
a consideration of the following description and
drawings, wherein:

Fig. 1 is an elevational view, partly in section,
of a cycle saddle embodying our invention;

55 Fig. 2 is a transverse section taken along the
line 2—2 of Fig. 1;

Fig. 3 is a rear perspective view of a receptacle
unit which we may employ, shown separately and
with the view rotated through 90°;

60 Fig. 4 is a fragmentary elevational view of a

modification of our invention, wherein the closure
element is in the form of a drawer;

Fig. 5 is a plan view of the modification of
Fig. 4;

Fig. 6 is a plan view of a modified type of draw- 5
er which we may employ; and

Fig. 7 is a section taken along the line 7—7 of
Fig. 6.

Referring now to the drawings, we have indi-
cated generally at 10 a saddle seat comprising a 10
body of any suitable construction, such as top
and bottom leather cover portions 11 and 12, and
an intermediate cushioning material 13, the pe-
ripheral portions of the body preferably having a
strip of binding material 14 secured thereto in the 15
usual manner.

Springs 15—15 secured to the under side of the
seat and a reach member 16 secured to the lower
20 end convolutions of the springs 15, and with the
forward end of the reach member secured to the 20
seat adjacent the pommel, form a mounting
means for the seat. The construction of the
mounting means constitutes no essential part of
our invention, and any suitable construction may
be employed.

Rearwardly of the springs 15 and preferably
closely adjacent thereto, we provide a receptacle
generally indicated at 17 formed by an angular
metal or the like plate having an upstanding wall
18 forming the front wall of the receptacle with
30 the top edge abutting the under side of the seat
10 and the lateral edges abutting depending wall
portions of the seat. The bottom portion 19 of
the plate forms part of the receptacle base and
also abuts the lateral wall portions of the seat,
35 being secured thereto by downturned end flanges
20—20 which are riveted or otherwise suitably
secured to the lateral wall portions of the seat.

As best illustrated in Fig. 3, the bottom portion
40 19 of the plate is provided with generally rec-
tangular slots 21 through which are projected
ears formed on a plate 22 to hingingly secure
the plate 22 to the portion 19 of the angle plate.
The rear portion of the plate 22 is of arcuate
45 form and is provided with a depending flange 23.
A rigid plate 24 curved to conform to the contour
of the saddle rear wall and adapted to form a
part thereof, is secured to the flange 23 of the
plate 22 by riveting. The plate 24 is externally
50 covered with leather similar to the cover portion
11 and internally is also preferably leather cov-
ered with the covering material joined by a pe-
ripheral binding strip 25.

Any suitable locking means may be provided
55 for locking the hingingly supported rear saddle
portion in a closed position and we have shown a
perforated strip 26 secured to a portion of the
saddle wall and a hook 27 secured to the plate
24 and adapted to be projected through the
60 strap and snapped to a locking position.

It will now be understood that a built-in receptacle is provided in the rear portion of the saddle which is of sufficiently rigid construction to reinforce the saddle in this zone, particularly the upstanding wall 18 and the base 19 of the angle plate contributes to this result. Also, the provision of such a receptacle is not apparent due to the built-in construction and due to the closure portion conforming in contour to the saddle generally.

Referring now to Figs. 4 to 7 inclusive, we have illustrated a construction generally similar to that previously described, wherein a drawer is removably supported by an angle plate comprising an upstanding wall 30 and a base 31, the base being provided with downturned lateral ears 32—32 whereby the plate may be riveted to the lateral wall portions of the saddle as previously described. The base has generally Z-shaped strips 33—33 welded thereto to form supporting guideways for the lateral edges of a plate 34, the rear portion of the plate 34 having a depending flange 35 to which is secured by riveting or the like a rigid plate 36 generally similar to the plate 24, previously described.

To prevent the plates 34 and 36 from being completely removed from the supporting plate 31, the plate 31 is slotted as indicated at 37 and a rivet 38 is projected through the plate 34 and the slot 31 and headed over.

The plate 36 is preferably leather covered internally and externally, and the locking means for securing to the saddle may comprise a resilient finger 39 secured to the plate 36 and adapted to ride over an abutment 40 secured to the rear wall of the saddle. Thus, a drawer arrangement is provided affording somewhat easier access to articles carried in the receptacle than the hinged closure construction.

Figs. 6 and 7 illustrate a drawer construction which may be substituted for the drawer of Figs. 4 and 5, and in this instance the plate 36 is secured to a metal plate comprising a base 44 and lateral upstanding walls 41—41, the walls 45 preferably being curved or converging upwardly to conform to the cut-away rear portion of the saddle. The laterally outwardly extending flanges 42—42, preferably formed by a crimping or the like operation, are adapted to engage the 50 guideways formed by strips 33—33 to support the drawer in open and partly open position.

Although we have shown and described modifications of our invention, we contemplate that numerous and extensive departures may be made 55 therefrom without departing from the spirit of our invention and the scope of the appended claims.

Having thus described our invention, what we claim is:

1. A cycle or like saddle of the type comprising a seat portion and a wall portion depending therefrom, an opening in the rear wall portion, a rigid receptacle under the seat portion comprising a rigid plate of angle construction providing an upstanding transverse wall peripherally engaging the under side of the seat and lateral wall portions, and a generally horizontally extending base abutting the lateral wall portions, means for securing the plate to the saddle seat and wall portions, and closure means for said opening supported by the base permitting access to the receptacle and comprising an outwardly

curved plate adapted in closed position to conform to and form a portion of the saddle rear wall.

2. A cycle or like saddle of the type comprising a seat portion and lateral wall portions depending therefrom, an opening in the wall portion, means providing a receptacle under the seat portion and reinforcing the seat, said means comprising a metal plate of angle construction including an upstanding transverse wall peripherally abutting the under side of the seat and lateral wall portions of the saddle and a generally horizontally extending base secured to the lateral wall portions of the saddle, closure means for said opening permitting access to the receptacle and forming a portion of the wall in closed position, said closure means comprising a rigid plate hingingly secured to the receptacle base, and means for locking the closure means in closed position. 10

3. A cycle or like saddle of the type comprising a seat portion and a wall portion depending therefrom, an opening in the rear wall portion, a rigid plate of angle construction under the seat portion including an upstanding transverse wall and a horizontally extending base, and means for closing said opening and adapted to form a portion of the wall in closed position, said closure means comprising a generally horizontally extending plate adapted to be slidably supported on the base and an upstanding rigid closure portion in closed position conforming generally to the saddle rear wall contour. 20

4. A cycle or like saddle of the type comprising a seat portion and wall portion depending therefrom, an opening in the rear wall portion, means reinforcing the seat portion and providing a receptacle thereunder comprising a rigid plate of angle construction including a transverse upstanding wall and a generally horizontally extending base, means securing the plate to the saddle seat and wall portions, elements secured to the base forming guideways extending longitudinally of the saddle, and a drawer adapted to be slidably supported by the base comprising a generally horizontally extending plate having its lateral edge portion slidably enclosed within the guideways, and an upstanding rear portion forming a closure means for said opening and in closed position conforming to the saddle wall. 30

5. A cycle or like saddle of the type comprising a seat portion and lateral and rear wall portions depending therefrom, an opening in the rear wall portion, means providing a receptacle under the seat portion and reinforcing the seat, said means comprising a metal plate of angle construction including an upstanding transverse wall peripherally abutting the underside of the seat and lateral wall portion of the saddle and a generally horizontally extending base secured to the lateral wall portions of the saddle, closure means for said opening permitting access to the receptacle forming a portion of the rear wall in closed position, said closure means comprising a rigid plate hingingly secured to the receptacle base and an upstanding relatively rigid arcuate portion adapted to abut peripheral portions of the opening formed in the rear wall with the closure means in closed position. 40
